CLAIM

The ornamental design for a vehicle air conditioner unit, substantially as shown and described.

DESCRIPTION

FIG. 1 is a rear elevational view of a vehicle air conditioner unit showing our new design;

FIG. 2 is a top plan view thereof;

FIG. 3 is a front elevational view thereof; and

FIG. 4 is an elevational view taken from one side thereof, the opposite side being a mirror image of the side shown.

The fragmentary broken line representation of a vehicle in FIG. 1 is for purposes of illustration only.
